UNITED STATES PATENT OFFICE.

HARRY H. VICKERS, OF CORONA, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed February 6, 1925. Serial No. 7,243.

This invention relates to means to facilitate handling and adjusting of superposed work-sheets around the platen of a type-writing machine. The invention is in the 5 nature of improvements which may be used with parts shown in the application of Jesse A. B. Smith, No. 598,066, filed October 31, 1922 (now Patent No. 1,524,756, dated February 3, 1925), in which all of the items of 10 successively typed statement or bill sheets are copied on a record or proof sheet, which record-sheet remains in the machine with a superposed carbon-sheet.

In said application the record-sheet and 15 its carbon are introduced at the rear of the platen, over an auxiliary paper-table. The bill-sheet is also introduced at the rear of the platen, but is conducted over the usual rear paper-table which is located behind the 20 auxiliary paper-table at the introductory side of the platen. The record-sheet is conducted behind a collating table at the front of the platen and upon which the bill-sheet may be adjusted relatively to the record- 25 sheet. At the completion of typing of each bill-sheet the usual feed-rolls are released to facilitate a rapid removal of the completed bill-sheet, and also enable a rapid insertion of a new untyped bill-sheet around the platen from the rear thereof. During such manipulation of the statement-sheets it is 30 desirable to prevent accidental displacement of the record-sheet. Accordingly there are provided holding devices or clamps which are normally ineffective, but which may be 35 rendered effective to hold the record-sheet against the platen prior to the release of the feed-rolls.

A feature of the present invention relates 40 to means automatically controlled by the feed-roll release lever to render the clamps effective during the initial movement of said lever, so that the record-sheet may first be gripped, after which a further movement 45 of said lever is effective to release the feed-rolls, to thus enable the rapid removal of the typed statement and insertion of an untyped statement, as previously stated.

Another feature of the invention relates 50 to means to enable erasures to be made on the record-sheet. To this end, the sheet-positioning table at the delivery side of the platen is removably supported on the platen-frame, so that it may be detached to

give access to the record-sheet at the rear 55 thereof. Said table is supported on a cross-bar which is provided at one end with a horizontal slot, so as to embrace a stud at one end of the platen-frame. The other end of the cross-bar is provided with a vertical 60 slot extending upwardly from its lower edge, so that the bar may be swung down to embrace a stud secured to the other end of the platen-frame. A thumb-screw is provided on the last-named stud by which the 65 detachable bar may be secured in place.

Another feature of the invention relates to the detachability of the record-sheet clamps with the front paper-table. To enable the removal of said clamps, they are 70 supported on the detachable cross-bar, said clamps being carried by a rock-shaft on said cross-bar to enable them to be swung to their effective and ineffective positions while the cross-bar is attached to the 75 platen-frame.

To operate said clamps, one end of the rock-shaft, upon which they are adjustably supported lengthwise thereof, is provided with a crank-arm to be engaged by a cam 80 pivoted on a bracket secured to the platen-frame, said cam being connected by means of a link to the feed-roll release lever to operate said rock-shaft, to thus throw the clamps against the platen when said feed- 85 roll release lever is operated to release the feed-rolls. The crank-arm of the clamp-supporting rock-shaft is so disposed relatively to the operating cam, on the platen-frame, that it may readily be removed from 90 the carriage without disturbing said cam while the collating table is being detached from the machine.

A further feature of the invention relates 95 to means to facilitate the temporary release of the record-sheet clamps, to thus enable an adjustment of the record-sheet relatively to the printing line, after the clamps have been rendered effective by the feed-roll release lever, and while said lever remains 100 in its operated position.

Still another feature of the invention relates to novel means to enable endwise adjustment of the front sheet-positioning table which is composed of two sections 105 individually adjustable, said adjustable means comprising brackets on the back of said table-sections to embrace the detach-

able cross-bar, and screws which bear against said cross-bar to secure the table-sections in their adjusted positions.

A still further feature of the invention relates to one or more side-edge gages on the auxiliary paper-table to position the record-sheet relatively to the front table, so as to bring about the proper relation lengthwise of the platen between record-sheet and statement-sheet, said side-edge gages being also effective to locate the record-sheet relatively to tabulating mechanism and computing mechanism, not shown, which may be like that of the Underwood bookkeeping machine, and which is caused to operate in certain columns on the work-sheets.

The side-edge gages are supported in a novel manner by means comprising a cross-bar located in front of the auxiliary paper-table, and they are adjustable lengthwise of said cross-bar. To this end, each gage comprises lips to embrace the upper and lower edges of said cross-bar, and a spring secured to the back of the gage to bear against said cross-bar and frictionally hold said edge-gage in its adjusted position. To prevent obstruction of the bottom edge of the record-sheet when it is desired to reversely feed it after its bottom edge has passed the lower edge of the side-edge gages, said gages are flared outwardly and extend into a groove in the auxiliary paper-table.

To further prevent obstruction of the record-sheet during reverse feeding operation, there is provided, substantially in the middle of the carriage, a guide on the cross-bar which supports the side-edge gages to prevent the bottom edge of the record-sheet, which tends to sag in the middle, from colliding with said supporting bar.

Other features and advantages will hereinafter appear.

In the accompanying drawings.

Figure 1 is a sectional side elevation of an Underwood bookkeeping machine, showing the invention applied thereto, the section being taken on the line 1—1 of Figure 4.

Figure 2 is a diagrammatic view, similar to Figure 1, but the collating table having been removed from the carriage, so that the carbon-sheet may be folded forward to enable erasures to be made on the record-sheet.

Figure 3 is a detail view, showing the yieldable connection between the crank-arm and the rock-shaft which supports the record-sheet clamps.

Figure 4 is a front view of the parts shown in Figure 1.

Figure 5 is a rear view of the collating table, showing its supporting bar, and the record-sheet clamps mounted on the rock-shaft carried by the supporting bar.

Figure 6 is a diagrammatic view similar to Figure 1, showing the feed-roll release lever operated sufficiently to grip the record-

sheet and its associated carbon-sheet just prior to the release of the feed-rolls.

Figure 7 is a view similar to Figure 6, but shows the feed-rolls released by a further movement of the feed-roll release lever.

Figure 8 is a view similar to Figure 7, but shows the record-sheet clamps temporarily released, while the feed-roll release lever is in its operated position, to enable an adjustment of the record-sheet relatively to the platen and printing lever.

Figure 9 is a detail view, showing the position to which the pin on the clamp-supporting rock-shaft has moved within a slot of a hub on the crank-arm when the handle for temporarily releasing the clamps is operated as in Figure 8.

A record-sheet 10 having a superposed sheet of carbon-paper 11, is first inserted in the machine, leading edge first, down an auxiliary rear paper-table 12 under the platen 13, co-operating with the feed-rolls 14 and 15, and up in front of the platen. The record-sheet may be supplied to the machine in the form of a roll at the rear thereof, and it is laterally guided by paper-gages 16 adjustably mounted on the table 12.

A statement-sheet 17 upon which it is desired to type data which must, at the same time, be copied on the record-sheet 10, is then inserted in the machine, leading edge first, down a paper-chute formed between the auxiliary rear table 12 and a rear paper-guide 18. The latter is fast to the platen-frame 19 by means of brackets 20 and screws 21. As it is desired to insert the statement sheet in front of the record-sheet without disturbing the position of the latter, means are provided whereby the feed-rolls may be rendered inoperative, while, at the same time, a pair of spring-operated paper-clamps 22 are simultaneously allowed to hold the record-sheet against the platen 13, which is revolutely mounted on a shaft 23 and journaled in the platen-frame. Then the statement-sheet is forced downwardly under the platen, up in front thereof and over a front table 24, to laterally position the same between the guiding edges 25 which form an integral part of said table 24. The feed-rolls are allowed to return to their normal or effective position, while, at the same time, the clamps 22 are thrown to their ineffective position. The type-bar 26 is then operated, and a line of typing is written upon the statement-sheet through the ribbon 27, and transferred to the record-sheet through the carbon-paper.

When all data which must be recorded on the record-sheet has been typed upon the statement-sheet, the latter is withdrawn, and a fresh sheet may be inserted in the machine. To withdraw the statement-sheet the feed-rolls must be released and the clamps 22 rendered effective, so that the statement-

sheet may be gripped by its leading edge 28, and pulled out of the machine without displacing the record-sheet.

It is sometimes desired to make erasures on the record-sheet, and in order to reach the same it will be necessary to remove the table 24, which is slidably mounted on an angular cross-bar 29, and to pull the carbon-paper forwardly, as shown in Figure 2. The table 10 may be detached from its supporting frames 30, which are fast to the platen-frame 19 by means of the screws 21 and 31, by loosening a finger-screw 32, so that the bar 29 may be swung upwardly at this end, and so 15 that a vertically-disposed slot 33 will disengage the screw. Then the other end, which has a horizontally-disposed slot 34, engaging a shouldered pin 35 fast to the frame 30, is withdrawn to take the table off the machine. As hereinbefore stated, in order to 20 make erasures on the record-sheet, the carbon-paper has to be swung forwardly out of the way, and, to this end, the clamps 22, which normally hold the carbon-paper and record-sheet on the platen, must consequently be moved out of the way. With this 25 object in view, the clamps 22 are mounted on a cross-shaft 36 which is rockably mounted on the bar 29. Said cross-shaft is 30 provided with a longitudinal groove 37 into which a rod 38, held under the pressure of a spring 39, is fitted to hold the clamps 35 radially located on the shaft, while at the 35 same time rendering the clamps 22 slideable therealong. The clamps 22 comprise a supporting member 40 and a downwardly-extending finger 41 which is fast to the member 40 by means of screws 42. At the 40 ends, the clamps are provided with pads 43 of rubber or other soft material to more effectively hold the paper, when a spring 44 actuates to turn the shaft 36, and to force the clamp downwardly.

It is sometimes desired to temporarily release the clamps while the feed-rolls are ineffective, and the clamps are consequently in their effective position. One of the reasons may be to insert a new record-sheet or to correct its creeping away while fed around the platen. To this end, there is provided a lever 45, shown under the pressure of a finger 46 in Figure 8. Said lever is fast to the shaft 36, and is operatively connected to a crank-arm or operating arm 46 loosely mounted on the shaft 36 by means of a spring 47 and a pin-and-slot arrangement 48, limiting the travel of the crank-arm or operating arm 46 relatively to the shaft 36 and normally holding said arm in the position shown in Figure 1. The spring 47 is held at one end on a pin 49 fast on the arm 46, and at the other end under a bent tab 50 of the lever 45.

In order that, when the feed-rolls are released by means of the lever 51 to allow

the insertion of the statement-sheet, the record-sheet may not be shifted out of place, and, in order to simplify the operation and render the device more efficient, there is provided linkage to simultaneously operate both the feed-rolls and the paper-clamps 22, that is to say, means whereby the clamps will be rendered effective during the first portion of the travel of the lever, and the feed-rolls will be rendered ineffective during the second portion of the travel. In this manner the record-sheet will be controlled at all times either by the feed-rolls or by the clamps, thus rendering its displacement impossible. The feed-rolls are revolubly mounted on the shafts 52 which are in turn journaled on supporting brackets 53 and 54, the latter being pivotally mounted on the cross-shaft 55. Said brackets are provided with downwardly-extending fingers 56 co-operating with the rockably-mounted shaft 57, which is in turn operated by the action of the crank 58 fast thereto, and is operatively connected to the arm 59 by means of a connecting link 60 through pins 61 and 62, the latter being fast to the arm 59 which forms an integral part of the lever 51, both being fast on a shaft 83 which is fulcrumed on the bracket 84, fast to the platen-frame 19. To control the function of the clamps 22 simultaneously with the operation of the feed-rolls, there is provided the intermediate finger-piece 63 fulcrumed on a screw 64 on the supporting frames 30. Said finger-piece 63 is operatively connected to the lever 51 by means of a link 65 which is mounted on a pin 66 fast to the finger-piece 63 at one end, while the other end is connected to the lever 51 at 67 on a rearwardly-extending arm 68, which forms an integral part of the lever 51. The finger-piece 63 is provided with a cam-face 82 which co-operates with a roller 69 fast on the crank-arm 46, so that when the finger 46 pulls the lever 51 forwardly from a position shown in Figure 1 to that shown in Figures 6 and 7 successively, the cam-face 82 will force the crank-arm 46 rearwardly, and due to its resilient connection between said arm, carrying the pin 49 fast thereon, and the spring 47 wound around the shaft 36, the clamps 22 are thrown to their effective position and held against the platen by the action of the lighter spring 44, also wound around the shaft 36.

The gages 16, designed to laterally locate the record-sheet 10, are operatively mounted upon a cross-bar 70 which is fastened to the table 12 by means of screws 71 fitting into an elongated slot 72 in the bar 70, which serves as means to adjust the bar parallelly to the platen. The gages are fast to guiding members 73 which are slidably mounted on the bar 70 and are held under the tension of a spring 74.

The front table comprises two sections 75

and 76, both supported by angular pieces 77 of which they form an integral part. There is provided screws 78 to locate the pieces 77 upon the cross-bar 29, so that the 5 two sections of the table may be adjustably moved along the cross-bar to suit the width of the statement-sheet.

It is sometimes desired to back up the record-sheet, and to prevent obstruction of 10 the bottom edge of the record-sheet against the paper-gages 16, the latter are provided with a downwardly-extending tab 79 which extends into a groove 80 formed at the lower end of the auxiliary table 12. To further prevent obstruction of the record-sheet during reverse feeding, a center guide 81 is mounted on the cross-bar 70, said guide being of the same general design as the gages 16, need not be described.

Variations may be resorted to within the scope of the invention, and portions of the improvements may be used without others.

Having thus described my invention, I claim:

1. In a typewriting machine, including a revolute platen and feed-rolls therefor, the combination of a rear table, a guide-plate for guiding a record-sheet at the introductory side of said platen, said rear table forming a chute for conducting a statement-sheet between the table and the guide-plate, a front table at the delivery side of said platen for laterally positioning the statement-sheet, a cross-bar for mounting the 35 front table, a rock-shaft rockably supported on said cross-bar, clamps operatively mounted on said rock-shaft co-operating with the platen to hold the record-sheet therearound, and means for simultaneously 40 releasing the feed-rolls and rendering the clamps **effective**.

2. In a typewriting machine, including a revolute platen and feed-rolls therefor, the combination of a rear table, a guide-plate 45 for guiding a record-sheet at the introductory side of said platen, said rear table forming a chute for conducting a statement-sheet between the table and the guide-plate, a front table at the delivery side of said platen for laterally positioning the statement-sheet, a cross-bar for mounting the front table, a rock-shaft rockably supported on said cross-bar, clamps operatively 50 mounted on said rock-shaft co-operating with the platen to hold the record-sheet therearound, means for simultaneously releasing the feed-rolls and rendering the clamps effective, and means whereby the front table, the rock-shaft and the clamps 55 may be manually removed from the machine, to manipulate the record-sheet.

3. In a typewriting machine, the combination of a revolute platen, feed-rolls and control mechanism therefor, including 60 an operating lever, resilient sheet-engaging

clamps at the delivery side of the platen, and means connected with the feed-roll-control mechanism to alternately render the clamps effective when the operating lever causes the feed-rolls to become ineffective, 70 said means including an operating arm for the clamps, a pivotally-mounted cam-lever for actuating the clamp-operating arm, and a link connecting the cam-lever and the feed-roll-operating lever. 75

4. In a typewriting machine having a platen, the combination with a collating table at the delivery side of the platen and having independent sections, of a detachable cross-bar angular in cross-section extending 80 in parallel relation with the platen, angular brackets secured to the rear of the collating table-sections and slidably embracing the cross-bar, and means on the brackets to lock the sections in adjusted positions relatively to the cross-bar and the platen. 85

5. In a typewriting machine, including a revolute platen, an auxiliary table at the introductory side of the platen, a cross-bar 90 adjustably mounted on said table, two side gages slidably mounted on said cross-bar, and springs for holding the gages in a fixed position upon the bar.

6. In a typewriting machine, including a revolute platen, an auxiliary table at the 95 introductory side of the platen, a cross-bar adjustably mounted on said table, two side gages and a guide disposed therebetween slidably mounted on said cross-bar, and springs for holding the gages and the guide 100 in a fixed position upon the bar.

7. In a typewriting machine, including a revolute platen, an auxiliary table at the introductory side of the platen, said table having a transversely-extending groove at the bottom thereof, a cross-bar adjustably mounted on said table above said groove, side gages having downwardly-extending tongues fitting into said groove and slidably mounted on said cross-bar, and springs 105 for holding the gages in a fixed position upon the bar. 110

8. In a typewriting machine, including a revolute platen, feed-rolls and controlling mechanism therefor including a lever, a double table forming a chute at the introductory side of the platen, a table at the delivery side of the platen adjustably mounted on a cross-bar for positioning a statement-sheet guided by said chute, means for laterally positioning a record-sheet, resilient clamps operatively mounted on the cross-bar disposed to hold the record-sheet and the carbon-paper on the platen against accidental shifting, said clamps connected to said feed-roll-controlling mechanism to be clamped when the feed-rolls are released, and means for guiding the record-sheet at the introductory side of said platen, said last-mentioned means including a cross-bar 115 120 125 130

adjustably mounted on the rear table, two side gages slidably mounted on said cross-bar, and springs for holding the gages in a fixed position upon the bar.

mounted thereon, said rock-shaft extending parallel to said cross-bar and journaled therein, means controlled by the feed-roll-controlling mechanism to simultaneously operate said clamps so that the record-sheet may be gripped by the clamps previous to releasing the pressure of the feed-rolls, means to render the clamps manually operable independently of the feed-roll-controlling mechanism, and means for rendering the clamps adjustable, said last-mentioned means including a slot in said rock-shaft and a resilient detent in the clamps disposed to hold the clamps against radial displacement relatively to the shaft and for positioning and holding the clamps.

14. In a typewriting machine including a revolute platen, feed-rolls and feed-roll-controlling mechanism, in combination, means for positioning a work-sheet including a record-sheet and a statement-sheet relatively to each other, said means including a front table for positioning the statement-sheet, clamps at the delivery side of the platen for holding the record-sheet while inserting the statement-sheet, means for operating the clamps through the feed-roll-controlling mechanism, means for operating the clamps independently of the feed-roll-controlling mechanism, and means at the rear of the machine for inserting both the statement-sheet and the record-sheet, the latter having means for laterally positioning the same previous to entering the platen.

15. In a typewriting machine including a revolute platen, feed-rolls and feed-roll-controlling mechanism, in combination, means for positioning a work-sheet including a record-sheet and a statement-sheet relatively to each other, said means including a front table for positioning the statement-sheet, clamps at the delivery side of the platen for holding the record-sheet while inserting the statement-sheet, means for operating the clamps through the feed-roll-controlling mechanism, means for operating the clamps independently of the feed-roll-controlling mechanism, and means at the rear of the machine for inserting both the statement-sheet and the record-sheet, the latter having means for laterally positioning the same previous to entering the platen, said last-mentioned means including a rear table, an auxiliary guide-plate between the table and the platen, a cross-bar fast upon the guide-plate, side gages slidably mounted upon said cross-bar, and a spring on said gages to facilitate the manual positioning of the gages along the bar, and means to permit the back feeding of the record-sheet, said last-mentioned means including downwardly-extending bends forming the edge of the gages, said bends engaging with a groove in the table and a center guide to prevent the bottom edge from sagging at the center and from striking the cross-bar upon which the gages and the center guide are mounted.

16. In a typewriting machine including a revolute platen, feed-rolls and feed-roll-controlling mechanism, in combination, means for positioning a work-sheet including a record-sheet and a statement-sheet relatively to each other, said means includ-

ing a front table for positioning the statement-sheet, clamps at the delivery side of the platen for holding the record-sheet while inserting the statement-sheet, means for operating the clamps through the feed-roll-controlling mechanism, means for operating the clamps independently of the feed roll-controlling mechanism, means at the rear of the machine for inserting both the statement-sheet and the record-sheet, the latter having means for laterally positioning the same previous to entering the platen, said last-mentioned means including a rear table, an auxiliary guide-plate between the table and the platen, a cross-bar fast upon the guide-plate, side gages slidably mounted upon said cross-bar, and a spring on said gages to facilitate the manual positioning of the gages along the bar, and means to permit the back feeding of the record-sheet, said last-mentioned means including downwardly-extending bends forming the edge of the gages, said bends engaging with a groove in the table and a center guide to prevent the bottom edge from sagging at the center and from striking the cross-bar upon which the gages and the center guide are mounted.

17. In a typewriting machine, including a platen-frame and a revolute platen therefor, a supporting frame on each end of the platen-frame, a channel-shaped cross-bar, means for removably mounting said cross-bar on the supporting frames, said means including a radially-disposed slot at one end of the cross-bar embracing a finger-screw on one supporting frame and a longitudinally-disposed slot at the other end of the cross-bar engaging a pin fast to the other supporting frame, and a collating table transversely adjustable on said cross-bar. 100

18. In a typewriting machine, including a platen-frame and a revolute platen therefor, a supporting frame on each end of the platen-frame, a channel-shaped cross-bar, means for removably mounting said cross-bar on the supporting frames, a collating table adjacent the delivery side of the platen adjustable on said cross-bar, a rock-shaft rockably supported on the cross-bar, resilient sheet-engaging clamps keyed to the rock-shaft, but adjustable lengthwise thereon, an operating arm fast to one end of the rock-shaft, said arm having a roller at its free end, and a cam-lever pivoted to the supporting frame adjacent that end of the rock-shaft carrying the operating arm, the roller on said arm coacting with the cam-portion of the lever, whereby on actuation of the cam-lever motion will be imparted to the rock-shaft through the operating arm to actuate the clamps. 110

19. In a typewriting machine, including a platen-frame and a revolute platen therefor, a supporting frame on each end of the platen-frame, a channel-shaped cross-bar, 130

means for removably mounting said cross-bar on the supporting frames, a collating table adjacent the delivery side of the platen adjustable on said cross-bar, a rock-shaft 5 rockably supported on the cross-bar, resilient sheet-engaging clamps keyed to the rock-shaft, but adjustable lengthwise thereon, an operating arm fast to one end of the rock-shaft, said arm having a roller at its free 10 end, and a cam-lever pivoted to the supporting frame adjacent that end of the rock-shaft carrying the operating arm, the roller of said arm lying in close proximity to the cam-portion of the lever to operate the rock-shaft and the clamps and removable therefrom upon the cross-bar and collating table 15 being detached from the supporting frames.

20. In a typewriting machine, including a platen-frame and a revoluble platen therefor, a supporting frame on each end of the platen-frame, a channel-shaped cross-bar, means for removably mounting said cross-bar on the supporting frames, a rock-shaft rockably supported on the cross-bar, resilient 25 sheet-engaging clamps keyed to the rock-shaft, but adjustable lengthwise thereon, an operating arm having a pin-and-slot connection with the rock-shaft at one end thereof, means for actuating the operating arm to 30 throw the clamps to effective position against the platen, and a lever keyed to the rock-

shaft to rock-shaft to rock said shaft in a reverse direction through the pin-and-slot connection, to temporarily release the sheet-engaging clamps from the platen. 35

21. In a typewriting machine, including a platen-frame and a revoluble platen therefor, a supporting frame on each end of the platen-frame, a cross-bar mounted on the supporting frames, a rock-shaft rockably supported on the cross-bar, resilient sheet-engaging clamps keyed to the rock-shaft, but adjustable lengthwise thereon, an operating arm having a pin-and-slot connection 40 with the rock-shaft at one end thereof, to limit the travel of said arm with respect to the rock-shaft, means for actuating the arm to throw the clamps to effective position against the platen and incidentally cause the arm to assume one extreme position of its travel with respect to the rock-shaft, a lever keyed to the shaft adjacent the arm, and spring means connecting the lever and arm to keep the latter in said position, the lever being operable against the action of the 45 spring to rotate the shaft in a reverse direction, to temporarily release the sheet-engaging clamps from the platen, the operating arm assuming the other extreme position of its travel with respect to the rock-shaft. 50 55

HARRY H. VICKERS.
